HARRY LEVISON, OF SAN FRANCISCO, CALIFORNIA

CLAMPING MEANS FOR MOUNTING PRINTING PLATES

Application filed February 1, 1928. Serial No. 251,029.

My invention relates to clamps particularly designed for securing to either wooden, composition or metallic blocks unmounted printing-plates such as electrotypes, stereotypes, half tones, zinc etchings and other plates useful in printing and allied processes. Heretofore printing-plates have been either permanently attached to their blocks or if detached therefrom the means provided for securing them to the blocks has been rather complicated and very expensive. A printing-plate permanently secured to its block is objectionable in that the space taken up by them in storing or shipping is excessive.

In general it is the object of my invention to provide a means whereby an unmounted printing-plate may be readily attached to either a wooden, composition or metallic block and which means is very inexpensive.

Another object of my invention is the provision of a clip provided with an inwardly extending lip and an inwardly extending projection or teat in combination with a grooved or channelled block on which a printing-plate is to be mounted.

Another object of my invention is the provision in combination with a chase, a block and means for securing said block within said chase, of means operated by said first mentioned means for simultaneously securing a printing-plate to said block.

Another object of my invention is the provision of a clamping means for printing-plates such that the printing-plate may be readily changed without disturbing the position of the surrounding furniture while the chase remains within the press.

My invention possesses other objects and features of advantage, some of which, with the foregoing, will be set forth in the following description of my invention. It is to be understood that I do not limit myself to the showing made by the said description as I may adopt various forms of my invention within the scope of the claims.

Referring to the drawings:

Fig. 1 is a plan view of a chase, a printing-plate and the clamping means by which the block and printing-plate are simultaneously secured in position.

Fig. 2 is a transverse section taken on the line 2—2 of Fig. 1.

Fig. 3 is a fragmentary transverse section showing in detail the construction and operation of my clamping device.

Fig. 4 is a detail perspective view of the clip used to clamp an unattached printing-plate to its block.

Fig. 5 is a fragmentary transverse section showing in detail a modification of my clamping device in operation.

My invention comprises a clip 1 provided at one of its ends with an inwardly extending lip 2 and with an inwardly extending projection or teat 3 intermediate its ends. This clip is used in combination with a block 4 which may be constructed either of wood or metal and is provided with laterally extending grooves, channels or indentations 5. If found desirable and as is well known to the trade this block may be made in sections and brought to the proper dimensions by the use of leads. The printing-plate 6 to be mounted on the block 4 is placed thereon as shown in the various figures and when necessary may be brought to type height by means of shims. In order to clamp the printing plate to the block these members are placed within a chase 7 of any standard construction and several of the clips 1 are disposed along the sides of the block with the lips 2 overhanging the beveled edges of the printing-plate and with the projection or teats 3 extending into the grooves or channels of the block, as shown in Figs. 2 and 3.

It is to be noted that the center line of the teats is slightly above the center line of the grooves or channels 5, and that the teats and grooves or channels are so positioned that the outer edge of the roof of the grooves will always be in contact with the upper tapered surfaces of the teats. This particular relation of parts results in a certain clamping or wedging action to be later described.

The block 4 is then clamped or secured in the chase 7 or other form retaining means by the use of suitable standard furniture 8 and by pairs of key operated wedges or quoins 9 or other suitable clamping means. The wedging action produced by the wedges 9 exerts a thrust on the clips 1 in a direction

perpendicular to the plane of said clips, thereby forcing the clips toward the block 4. By so moving the clips 1 toward the block 4, the upper surfaces of the teats 3 are made to engage the roof of the channels or grooves 5 and due to the inclined surfaces of the teats, a vertical component of the lateral thrust is produced. This urges or wedges the clips 1 downwardly as well as inwardly, causing the lips 2 to engage the beveled edges of the printing-plate 6 and thereby clamping the printing-plate 6 and the block 4 together. The wedging action produced by the clips is of course due entirely to that portion of it lying above the center line of the teats.

15 The teats 3 may of course be replaced by laterally extending tapered projections and the groove 5 may extend either the full length of the block 4 or may be merely long enough to accommodate the teats 3.

20 The clips 1, as is shown in Fig. 5, may be provided with extending lips 11 at both of its ends, which, in this instance, extend inwardly, one to engage the beveled edges of the printing-plate and the other to replace the teats as described above and to engage the outer edge of the roof of the channels or 25 grooves within the block. The angles made by the lower lip or by the upper surface of the teats with the normal to the clip is preferably less than the corresponding angle made by the upper lip.

30 From the above disclosure it will be noted that I have provided a simple construction whereby a printing-plate may be secured to a block simultaneously with and by the same operation by which the block is positioned within the chase. A plurality of printing-plates may be set up within a single chase and each or any one of them may be easily and quickly changed without taking the chase from the press and without disturbing the surrounding furniture thereby effecting a considerable saving in time. The apparatus required is all standard with the exception of the block and clips used which are very readily and economically manufactured, and the time of "makeready" is materially decreased. These two factors, economy of time and economy of materials required for "make ready" make it possible to handle printing-35 plates unmounted, thereby effecting a material saving in storing and shipping costs.

40 It is to be understood that by the use of the word chase I intend to include those other means which are useful in retaining a form in position for printing and which are not particularly designated as chases but which perform substantially the functions thereof.

45 I claim:

1. As a new article of manufacture for use in clamping printing-plates to a block, a clip provided with an inwardly extending lip and an inwardly extending projection spaced

from said lip and adapted to engage said block.

2. As a new article of manufacture for use in clamping printing-plates to a block a clip provided with an inwardly extending lip at one of its ends and a tapered inwardly extending projection disposed below said lip.

3. As a new article of manufacture for use in clamping printing-plates to a block, a clip provided with an inwardly extending lip at one of its ends and an inwardly extending teat disposed below said lip.

4. As a new article of manufacture for use in clamping printing-plates to a block, a clip provided with an inwardly extending lip at one of its ends and inwardly extending teat intermediate its ends.

5. In combination with a block for detachably mounting printing-plates, a clip provided with an inwardly extending lip for engaging the tapered edges of a printing-plate below the printing plane, and means on said clip for positively securing said plate to said block upon a movement of said clip substantially parallel to said printing plate.

6. In combination with a block for detachably mounting printing-plates, a clip provided with an inwardly extending lip and an inwardly extending teat.

7. In combination with a block for detachably mounting printing-plates, a clip provided with means for pressing a printing-plate against said block when said clip is moved in a direction perpendicular to its own plane and parallel to the plane of the printing plate.

8. In combination with a block for detachably mounting printing-plates, a clip provided with means for engaging the edge of a printing-plate and means for pressing said printing-plate against said block when said clip is moved in a direction substantially parallel to the plane of the printing plate.

9. In combination with a channeled block for detachably positioning unmounted printing-plates, a clip provided with means for engaging the edge of a printing-plate and means cooperating with the channels of said block for pressing said printing-plate against said block when the clip is moved in a direction perpendicular to its own plane.

10. In combination with a block provided with lateral indentations, a plurality of clips provided with inwardly extending lips and inwardly extending tapered projections, the center line of said projections being normally disposed above the center line of said indentations.

11. In combination with a chase, furniture and a block provided with a laterally disposed groove, a plurality of clips each provided with an inwardly extending printing-plate-engaging-lip and an inwardly extending teat, said teat being adapted to engage the roof of said groove so that a thrust

on said clips normal to their plane produces a vertical component tending to press said block and plate together.

12. In combination with a chase, a block and means for securing said block within said chase, means operated by said first mentioned means for simultaneously securing a printing-plate positively to said block.

13. In combination with a chase, a block and furniture, means whereby a printing plate may be positively secured to said block simultaneously with and by the same operation by which the block is secured within said chase.

14. In combination with a chase, a block, furniture and clamping means, means whereby the engaging faces of a printing-plate and the block are positively pressed together by the same operation by which said block is secured within the chase.

15. In combination with a block for detachably mounting printing plates, a clip provided with means for engaging the edge of a printing plate substantially below the printing plane, and other means on said clip for positively securing said plate to said block upon substantially a movement of said clip parallel to said printing plane.

In testimony whereof, I have hereunto set
30 my hand.

HARRY LEVISON.
